UNITED STATES PATENT OFFICE.

JOSEPH H. FINK, OF KANSAS CITY, MISSOURI.

ROCKER-CUSHION.

SPECIFICATION forming part of Letters Patent No. 674,500, dated May 21, 1901.

Application filed June 3, 1899. Serial No. 719,214. (No model.)

To all whom it may concern:

Be it known that I, JOSEPH H. FINK, a citizen of the United States of America, residing in Kansas City, in the county of Jackson and State of Missouri, have invented a new and useful Improvement in Rocker-Cushions, of which the following is a specification, reference being had therein to the accompanying drawings.

10 My invention relates to improvements in rocker-cushions. It is adapted to be used in connection with chairs, cribs, rocking-horses, and similar articles which are provided with rockers.

15 My invention is of the class in which the under side of the rocker has secured to it an inflatable tube of resilient material.

20 The object of my invention is to provide the two inflatable tubes of a rocking-chair with means by which the tubes may be inflated and also retain an equal fluid-pressure in the two tubes at all times.

25 My invention also provides a construction in which the ends of the inflatable tubes are protected by the rocker, at the same time dispensing with the use of caps or other coverings for the ends of the tubes.

In the accompanying drawings, which illustrate my invention, Figure I represents a perspective view of a rocking-chair provided with rocker-cushions of my invention. Fig. II represents a vertical sectional view of the inflating-valve and connections. Fig. III represents an end view of the inflatable tube, with the rocker shown in cross-section. Fig. IV represents a longitudinal sectional view of one end of a rocker and tube. Fig. V represents a side elevation of a rocker and resilient cushion, a portion of the rocker being shown in vertical section. Fig. VI represents a view similar to Fig. IV, showing a modification of the securing device for the end of the inflatable tube.

Similar letters of reference indicate similar parts.

45 A indicates the rocker, which is provided in its under side with a longitudinal groove, which follows the curve of the rocker and near its ends is curved downwardly or reverse 50 the curve followed by the central portion of the groove. The object of the reverse curves in the groove will be explained hereinafter.

In each groove is placed an inflatable tube B, of soft rubber preferably. The ends of the tube B are solid and integral with the body of the tube. The upper and lower sides of the solid ends of the tube B taper or converge toward the ends. By reason of this tapering the end exposed to injury is small and caps for its protection may be dispensed with. The reverse curve in the groove in the rocker is to permit a snug fit of the tapered end of the tube B. In order to secure the said solid ends of the tubes B closely to the under side of the rocker, a transverse screw C extends into the rocker A at each end of the tube B and into the solid end of the tube. In order to have the screw C have a secure hold of the rubber tube B, the tube is preferably provided with a securing device D, embedded in the rubber and consisting of metal, wood, or other suitable substance. This securing device D may be provided with a threaded hole adapted to receive the threaded end of the screw, as shown in Fig. IV, or it may be used simply 75 as a washer, as shown in Fig. VI. The tube B may be inflated in any desirable manner, as by a valve E, which may be of the ordinary kind employed in connection with bicycle-tires.

80 In order to always have an equal fluid-pressure in both the rockers, I connect the two by means of the tubes F, which are preferably located in longitudinal conduits provided in the forward chair-legs and extend therefrom to an inflating-valve E, located between the chair-legs G and just below the seat of the chair. The other ends of the tubes F are interiorly connected with the tubes B. By introducing air into the valve F both tubes 85 are inflated at the same time. If one tube should leak a trifle, the air passing from the other tube would always preserve an equal pressure in both tubes. This is desirable, as both rocker-cushions yield alike under the 90 weight of a person when subjected to the same air-pressure, and the rocking motion is then even.

95 My invention is capable of many modifications without departing from its spirit.

Having thus described my invention, what I claim, and desire to secure by Letters Patent, is—

1. In rocker-cushions, the combination with

the rockers of a chair, crib or similar article, of inflatable tubes secured one to each rocker, two legs of the chair, one on each rocker, provided each with a longitudinal conduit communicating with the adjacent tube, and a tubular connection between the two conduits, substantially as described.

2. In rocker-cushions, the combination with the rockers of the kind described, of two legs, one on each rocker and each provided with a longitudinal conduit, inflatable tubes secured one to each rocker, a tubular connection between the tubes extending through the said conduits, and means by which the tubes may be inflated, substantially as described.

3. In rocker-cushions, the combination with rockers of the kind described, provided each on their under sides with a longitudinal groove, of the two legs, one on each rocker and provided each with a longitudinal conduit connecting with the groove in the adja-

cent rocker, an inflatable tube located in each groove, and a tubular connection between the two tubes and extending through the said conduits, substantially as described.

4. In rocker-cushions, the combination with a rocker of the kind described provided with a curved longitudinal groove in the under side thereof, the said groove being reversely or downwardly curved at its ends, of a resilient tube secured lengthwise in the said groove, the ends of the tube being tapered thereby avoiding the reverse curving of the under side of the tube, substantially as described.

5. In testimony whereof I have hereunto affixed my signature in the presence of two witnesses.

JOSEPH H. FINK.
